UNITED STATES PATENT OFFICE

EDWIN G. WEISSMAN, OF EASTON, PENNSYLVANIA, ASSIGNOR TO INDIVIDUAL DRINKING CUP COMPANY, INC., OF EASTON, PENNSYLVANIA, A CORPORATION OF PENNSYLVANIA

DISPENSER

Application filed December 6, 1930. Serial No. 500,641.

My invention relates to new and useful improvements in dispensers more particularly adapted for dispensing receptacles such as paper cups or the like.

5 The principal object of the invention resides in the provision of novel means for properly holding a stack of nested articles and for feeding the same to position to be dispensed, said means including a follower 10 adapted to be received on the stack and of a size to normally operate freely within a dome or container in which the stack is housed with its outer surface or edge in such close proximity to the inner wall or surface of the dome or container as to prevent swinging movement of the upper end of the stack, it being understood that by a slight lateral movement of the follower the same would engage the wall of the dome or container.

20 A further object of the invention consists in providing a follower of a construction adapted to encircle the uppermost article of the stack, said follower being formed interiorly so as to properly seat the end of the article therein and to snugly engage the outer surface of the article.

25 Still another object of the invention resides in the formation of the dome or container as well as the follower in such a manner that the follower will at all times be retained within the dome or container and will not be removed from the container or dome even when all of the articles of the stack have been dispensed, this allowing the follower to always be positioned within the container or dome and to be engaged by the article or articles when a new supply is positioned within the dome or container.

30 40 With the above and other objects in view, which will appear as the description proceeds, my invention consists in the novel details of construction and arrangement of parts, described in the following specification and illustrated in the accompanying drawings, and while I have illustrated and described the preferred embodiments of the invention, as they now appear to me, it will be understood that such changes may be made as will fall within the scope of the appended claims.

In the drawings:—

Fig. 1 is a front elevation of a dispensing machine with my improved form of follower in position.

55 Fig. 2 is a bottom plan of the follower.

Fig. 3 is a section on the line 3—3 of Fig. 1 with the articles to be dispensed shown in elevation.

60 Fig. 4 is a transverse vertical section through a portion of the base of the machine and dome or container for the stack, my improved form of follower being shown in elevation and in position within the container or dome after all of the articles of the stack have been removed.

65 Fig. 5 is a fragmental vertical section through a dome or container and a modified form of my follower with a portion of a stack of articles shown in side elevation.

70 Fig. 6 is a bottom plan of the modified form of follower; and

75 Fig. 7 is a fragmental vertical section through a portion of a dome or housing, with my modified form of follower shown in side elevation, the dome or housing being shown in inverted position to receive a stack of articles.

80 In the drawings 1 indicates a base of a dispensing machine in which any desired form of article engaging and dispensing mechanism may be positioned and operated in any suitable manner such as by a lever which I have indicated generally at 2. However, it will be understood that the dispensing mechanism forms no part of the present invention and, if desired, the base may be of that type used in the so-called pull type of dispenser in which the terminal article is adapted to be engaged by the fingers and removed from the stack. At 3 I have shown a dome or container adapted to house the stack 4 of the articles to be dispensed, in the present instance the dome or container being shown as of glass although I wish it understood that it may equally as well be made of metal or any other suitable material. The articles forming the stack 4 are shown in nested formation with their open ends positioned towards the dispensing opening of the base, the articles also being shown as of tapered

100

formation with a rim or bead formed around the open end to be engaged by the fingers or suitable dispensing mechanism. A metal ring or band 5 surrounds the lower end of the dome or container and is secured there-to by plaster of Paris 6 or other suitable material. The ring or band 5 is adapted to be received, with the lower end of the dome or container, within the open top of the base 1 and to limit the downward movement there-of, with the dome or container, an outwardly directed flange 7 is formed around the upper edge of the ring or band and normally engages the upper edge or top of the base 1, as shown more particularly in Fig. 4 of the drawings. The lower end of the ring or band 5 is formed with an inwardly directed flange 8 having its inner surface inclined as shown at 9, for a purpose to be later described, and with its inner edge 10 terminating inwardly of the interior diameter of the dome or container 3. The purpose of this will be later apparent.

At a I have indicated generally my improved form of follower which is of ring-like formation including the tapered wall 11, the outwardly directed horizontal flange 12 formed on its upper edge, and the flared portion or apron 13 formed at the lower edge. The rim or follower is adapted to surround the upper end of the stack of articles as shown more particularly in Figs. 1 and 3 of the drawings, and the inclined wall 11 will engage the outer surface of the uppermost article of the stack, the wall 11 being inclined conforming to the taper of the article. The outer edge of the flange 12 and the bottom edge of the flared portion or apron 13 will be positioned to normally be in close proximity to the inner surface or wall of the dome or container and to hold the upper end of the stack against swinging movement such as would bring the articles of the stack out of direct vertical position or out of alignment one relative to the other. By the use of this form of follower the stack will be urged towards the base or dispensing opening of the machine, the follower being of sufficient weight to serve this purpose.

In order that the follower may always be positioned ready for use the lower edge of the flared portion or apron 13 is of slightly greater diameter than the opening at the lower end of the ring or band 5. As shown more particularly in Fig. 4 of the drawings when all of the articles are removed from the device or machine the lower edge of the follower or ring will engage the inner edge 10 of the flange 8 formed on the ring or band 5. By holding the follower at all times within the dome or container there is no chance for loss or for the user to neglect to place the same within the dome or container when replenishing with articles. As the articles are being placed in the dome or container, through the

lower open end thereof, the innermost article and the end of the stack of articles will be guided by the inclined portion or apron 13 to project through the opening in the follower and to be engaged by the wall 11.

70

In Figs. 5, 6 and 7 of the drawings I have illustrated a slightly modified form of my invention wherein the follower while encircling the upper end of the stack is closed at its top and cooperates with the closed end of the dome or container to form an air cushion when the dome or container is in inverted position as shown in Fig. 7. It is the usual practice, in replenishing the dome or container with articles, to invert the dome and to allow the articles to drop therein. Naturally when the dome or container is inverted the follower drops to the closed end thereof and it is desirable to provide means whereby the follower will not impart a sharp blow to the end of the dome or container, this being of particular advantage when the dome or container is formed of glass. The outer edge or wall of the follower is in close proximity to the inner wall of the dome or container and as the follower is moved towards the closed end of the inverted container or dome only a small portion of air is allowed to pass around the follower. Thus air is trapped between the follower and closed end of the dome or container to form a cushion and allow the follower to be retarded in its movement towards the closed end of the dome or container and prevent sharp contact thereof such as would cause breakage.

80

In that form of the invention illustrated in Figs. 5, 6 and 7 of the drawings the follower consists of the flat top portion 14, the depending circumferentially extending side edge 15, and the inwardly directed ribs 16. The inner edges of the ribs 16 are tapered or inclined as shown at 17 to guide the end of the stack of the follower and slightly beveled or inclined as shown at 18 to conform to the taper of the body of the articles or receptacles. By reference to Fig. 5 it will be seen that the top 14 of the follower will rest directly upon the top of the stack with the flange 15 surrounding the upper end of the stack and the edges 18 of the ribs 16 in such close proximity to the outer surface of the terminal article as to prevent swinging of the stack relative to the follower. At the same time the outer surface of the follower is in such close proximity to the inner surface of the dome or container as to allow but a very slight lateral movement of the follower within the dome or container although allowing free vertical movement thereof. The outer diameter of the modified form of follower is such as to prevent the passage thereof through the open end of the dome or container it being understood that when all of the articles have been dispensed that the lower edge of the follower will engage the edge 110

10 on the inwardly directed projection 8 of the ring or flange 5 carried by the lower end of the dome.

From the above detail description it is 6 thought that the construction, operation, and advantages of my invention will be clearly understood. It will be seen that the follower at all times holds the articles of the stack in true vertical position, acts as a weight for 10 feeding the articles to the dispensing opening or mechanism and will be retained within the dome or container even when all of the articles have been removed. At the same time the formation of the follower allows for the 15 end of the stack to be guided thereto when inserting the articles into the dome or container. In the past considerable difficulty has been experienced in holding the stack of articles in a true vertical position and prevent- 20 ing the upper end thereof from swinging towards the side of the dome or container particularly when most of the articles have been removed or where only a few of the articles remain in position. This objection is over- 25 come with the use of my follower and at the same time the follower is always held within the dome or container against loss.

Having fully described my invention what I claim as new and desire to secure by Letters 30 Patent is:—

1. In combination with a dispenser includ- 35 ing a housing for a stack of articles to be dis- pensed, a ring-like follower adapted to be sup- ported by the stack and to receive the upper end thereof which projects therethrough, said follower having a central tapered portion engageable with the body of the article, a horizontal flange on the upper end, and an outwardly flared portion on the lower 40 end, the edge of the horizontal flange and the edge of the flared portion extending into close proximity to the inner surface of the housing.

2. In combination with a dispenser includ- 45 ing a base, a readily removable housing normally supported by the base and adapted to receive a stack of the articles to be dispensed, said housing having a closed end and an open end adapted to register with a dispensing opening in the base, a projection at the open end of 50 the housing extending inwardly to overlie the interior diameter of the housing but permitting dispensing of the articles, and a follower operable in the housing and adapted to be supported by the stack of articles, the fol- 55 lower being of a diameter permitting sliding movement in the housing but adapted to be engaged by the inwardly directed projection at the open end of the housing whereby it will be held within the confines of the housing 60 when all of the articles of the stack have been dispensed or when the housing is removed from the base.

3. In combination with a dispenser includ- 65 ing a base, a readily removable housing nor- mally supported by the base and adapted to

receive a stack of the articles to be dispensed, said housing having a closed end and an open end adapted to register with a dispensing opening in the base, a ring-like member sur- 70 rounding the open end of the housing and provided at its upper end with an outwardly directed flange adapted to engage and overlie the base and at its lower end with an inwardly projecting flange overlying the interior di- 75 ameter of the housing but permitting dispens- ing of the articles therethrough, and a fol- lower operable in the housing and adapted to be supported by the stack of articles, the fol- 80 lower being of a diameter permitting sliding movement in the housing but adapted to be engaged by the inwardly directed flange of the ring at the open end of the housing where- 85 by it will be held within the confines of the housing when all of the articles of the stack have been dispensed or when the housing is removed from the base.

In testimony whereof I hereunto affix my signature.

EDWIN G. WEISSMAN.
